UNITED STATES PATENT OFFICE.

JAMES LYALL, OF NEW YORK, N. Y.

DESIGN FOR A PATTERN FOR WOVEN FABRIC.

SPECIFICATION forming part of **Design No. 24,164**, dated **April 2, 1895**.

Application filed January 24, 1895. Serial No. 536,137. Term of patent 7 years.

To all whom it may concern:

Be it known that I, JAMES LYALL, a citizen of the United States, residing in the city, county, and State of New York, have invented

5 a new Design for a Pattern for a Woven Fabric, of which the following is a specification.

This woven fabric usually has heavy threads and is known as canvas, and is used in bicycle tires.

10 The leading feature of the design of this pattern consists of parallel stripes crossing the fabric diagonally, one set of stripes being plain and the intermediate stripes subdivided into narrow longitudinal stripes in which the lines in one stripe are at right angles to those in the similar adjoining stripes.

15 In the drawings, Figure 1 shows a piece of the woven fabric on a small scale so as to indicate the general proportion and appearance

of the stripe to the width of the woven fabric, 20 and Fig. 2 is a view of one end of the stripe of a size sufficiently large to show the design woven in the stripes extending across the fabric.

The plain stripe F, passes diagonally across 25 the fabric and the intermediate parallel stripes G, are subdivided into narrower stripes 4, and 5, the lines in the stripes 4, being at right angles to those in the stripes 5, and the plain stripe F, has a narrow central line 7. 30

I claim—

The design for a pattern for a woven fabric substantially as described and shown.

Signed by me this 14th day of January, 1895.
JAMES LYALL.
